(57) **CLAIM**

The ornamental design for a jewelry chain, as shown and described.

DESCRIPTION

FIG. 1 is a perspective view of one embodiment of one link of our new design used to form a jewelry chain showing our new design;

FIG. 2 is a front view thereof;

FIG. 3 is a top view thereof;

FIG. 4 is a bottom view thereof;

FIG. 5 is a side elevation view thereof;

FIG. 6 is a cross section taken through line 6—6 of FIG. 2; FIG. 7 is a perspective view of a jewelry chain formed from the links of FIG. 1.

FIG. 8 is a perspective view of a second embodiment of a link of our new design, such second embodiment being of hollow construction as opposed to the first embodiment which is of solid construction; the front view thereof being the same as shown in the link of FIG. 2; the bottom view being the same as shown in the link of FIG. 4; the side elevation view being the same as shown in the link of FIG. 5;

FIG. 9 is a top view of the link of FIG. 8;

FIG. 10. is a cross section taken through line 10—10 of FIG. 2; and,

FIG. 11 is a perspective view of a jewelry chain formed from the links of FIG. 8.
